UNITED STATES PATENT OFFICE.

JOHN F. O'CONNOR, OF CHICAGO, ILLINOIS, ASSIGNOR TO WILLIAM H. MINER, OF CHAZY,
NEW YORK.

RAILWAY DRAFT-RIGGING.

1,303,381.

Specification of Letters Patent. Patented May 13, 1919.

Application filed July 29, 1918. Serial No. 247,068.

To all whom it may concern:

Be it known that I, JOHN F. O'CONNOR, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, forming a part of this specification.

This invention relates to improvements in railway draft riggings.

The object of the invention is to provide a relatively inexpensive efficient friction gear for railway draft riggings, and more particularly, such a friction gear as employs torsion bars.

In the drawing forming part of this specification, Figure 1 is a horizontal, longitudinal, sectional view of a portion of a railway car and illustrating my improvements in connection therewith. Fig. 2 is a vertical, sectional view, taken on the line 2—2 of Fig. 1. Fig. 3 is a sectional view, taken on the line 3—3 of Fig. 1. Fig. 4 illustrates one of the followers employed with my improvements. Fig. 5 is a view similar to Fig. 1, but illustrating another embodiment of the invention. Fig. 6 is a view similar to Fig. 2, but taken on the line 6—6 of Fig. 5. Fig. 7 is an inner faced view of one of the followers. And Fig. 8 is a detailed, sectional view, taken on the line 8—8 of Fig. 5.

In said drawing and referring first to the construction illustrated in Figs. 1 to 4, 10—10 denote the draft sills of the car, 11 the center bolster casting, 12 a draw bar, and 13 a yoke. Secured to the draft sills 10 and depending therefrom is a comparatively heavy casting 14, as clearly shown in Fig. 2. Also secured to the under sides of said sills and at the rear of the bolster is a second casting 15, as shown in Fig. 3.

In carrying out my invention, I employ 45 preferably a pair of torsion bars 16 which are arranged parallel to or extend lengthwise of the draft sills. Said torsion bars have their inner ends carried by heavy ratchet wheels 17—17, the ratchet wheels 17 having hubs axially recessed to non-rotat-

tively receive the ends of the torsion bars. Said bars extend through suitable openings in the casting 15 and the ratchet wheels 17 are located on the rear side of said casting 15. The ratchets 17 are oppositely arranged 55 and coöperable therewith are suitable heavy dogs 18 pivoted to the casting 15. To hold the dogs 18 against accidental displacement, I employ a casting 19 detachably bolted to the casting 15, said casting 19 having shoulders 20 which engage the dogs 18 and prevent the latter from accidentally leaving the ratchet wheels. In this manner, it is evident that the rear or inner ends of the rods 16 60 are prevented from rotation, one in one direction and the other in the opposite direction.

At the forward ends, the bars 16 are provided with heavy upstanding levers 21, as clearly shown in Fig. 2. These levers or 70 lever arms 21 are formed at their upper ends with oppositely arranged sets of wedge-acting faces or surfaces, as indicated at 22—22 in Fig. 1 and with which coöperate corresponding wedge faces 23—23 formed on the 75 sides of the front and rear followers 24 and 25. The followers 24 and 25 are normally separated a distance corresponding to the permissible movement of the draw bar, said followers being held against movement in 80 one direction by suitable stop shoulders 26—26 formed integrally with the casting 14. As will be apparent from an inspection of Figs. 1 and 2, the lever arms 21 are held 85 against longitudinal movement and are confined to a twisting or rocking movement between the shouldered portions 26 of the casting 14. To support the rods and levers 21, a bottom plate 27 is provided which is detachably bolted to the casting 14, as clearly 90 indicated in Fig. 2.

The operation is as follows: Upon inward movement of the draw bar and the front follower 24, it is evident that the levers 21 will be forced apart, that is, the right 95 hand lever as viewed in Fig. 2, will be twisted in a clockwise direction and the other lever 21 in a counterclockwise direction. In this manner, the torsion or twist is placed upon the bars 16 and inasmuch as 100

the inner ends of the latter are held against rotation in these particular directions, the bars will act as heavy springs in absorbing the shock. Similarly, upon outward movement of the draw bar, the rear follower 25 will force the levers 21 in opposite directions and the draft shocks thereby absorbed.

By providing the ratchet arrangement at the inner ends of the bars 16, as hereinbefore described, it is evident that any desired degree of preliminary torsion can be imposed upon the bars 16 by merely rotating the ratchet wheel 17 correspondingly and for this purpose, the hubs of the ratchet wheels 17 are made square, as indicated at 28, so as to receive a claw bar or other suitable tool for the purpose indicated.

The device can be comparatively cheaply manufactured and inasmuch as the spring elements proper are in the form of bars, the latter may be replaced or renewed at a minimum of expense.

In the construction illustrated in Figs. 5 to 8, inclusive, a pair of torsion bars 116 is employed the same as in Fig. 1 and the rear ends of the bars 116 are secured in the same manner, which need not here be discussed. In the forms shown in Figs. 5 to 8, the bars 116 are located between the center sills 30 rather than below the sills and consequently the center bolster casting 111 is suitably apertured as indicated at 30 to accommodate the bars 116.

Mounted within the yoke 113, which is operatively connected to the draw bar, are front and rear followers 124 and 125. Between the said followers is a transversely extending heavy block or plate 31 which is held stationary by any suitable means, such as the two heavy transversely extending bolts 32—32 that pass through said block 31 and through suitable perforations in the draft sills and in reinforcing plates 33—33 secured to the outer faces of the sills. The rear follower 125 is suitably apertured, as indicated at 34, to permit the torsion bars 116 to pass therethrough.

Each of the followers 124 and 125 is provided on its inner side with right and left series of female steep pitch spiral threads 35 and 36. Coöperable with the steep pitch threads of the followers are four male members 37—37 that slide within the threads of the followers. The members 37 are arranged in pairs back to back and bear on the opposite faces of the block 31, and the members 37 are centrally recessed so as to fit over the torsion bars 116 and rotate in unison therewith. The block 31 is apertured, as indicated at 38 to accommodate the bars 116 which pass therethrough.

In operation, upon inward movement of the draw-bar the front follower 124 will be forced rearwardly and consequently the co-operating members 37 will be rotated, the

right hand one in a clockwise direction and the left hand one in a counterclockwise direction, as viewed in Fig. 6. Similarly, upon forward movement of the draw bar, the rear follower 125 will move forwardly and cause a corresponding rotation of the rear set of members 37 with consequent twisting or torsion of the bars 116. By employing right and left sets of threaded followers and members 37, tendency of the followers to be 75 themselves twisted is neutralized.

I claim:

1. In a railway draft rigging, the combination with draft sills, draw bar and yoke-acting means, of torsion rods arranged parallel to the sills and prevented against rotation at points therein, followers, and means between said followers and said rods for translating longitudinal movement of said followers to a twisting movement of said rods.

2. In a draft rigging for railway cars, the combination with draft sills, draw bar, yoke-acting means and followers, of torsion bars extending lengthwise of the sills, 90 means for holding the rear ends of said bars against rotation, and means interposed between said followers and the free ends of said bars for twisting the latter upon either inward or outward movement of the draw 95 bar.

3. In a railway draft rigging, the combination with draft sills, draw bar, yoke-acting means and followers, of longitudinally extending torsion bars, means for adjustably 100 holding the rear ends of said bars against rotation, and means interposed between said followers and the forward ends of said bars for translating linear movement of said followers into a twisting movement of said 105 bars.

4. In a railway draft rigging, the combination with draft sills, draw bar and yoke-acting means, of a plurality of torsion bars extending lengthwise of the sills and disposed therebetween, means for holding said bars against rotation at their inner ends, followers, members non-rotatably mounted on said torsion bars at their forward ends, and means for rotating said members upon relative approach of the followers.

5. In a railway draft rigging, the combination with draft sills, draw bar, yoke-acting means, and followers, of a pair of torsion bars extending lengthwise of the sills, 120 means for holding the rear ends of said bars against rotation, one bar in one direction, and the other bar in the opposite direction, and means interposed between said followers and the forward ends of said bars for imparting opposed twisting movements to said bars upon relative approach of said followers.

6. In a railway draft rigging, the combination with draft sills, draw bar and yoke- 130

acting means, of a plurality of straight torsion bars, means for translating linear movement of the draw bar to twisting movements of said rods and always in the same directions upon either buff or draft action, and means for adjusting the initial tension of said rods.

In witness that I claim the foregoing I have hereunto subscribed my name this 26th day of July, 1918.

JOHN F. O'CONNOR.
